Agnes S. Selverstone, New York, N. Y., assignor to Best & Co., Inc., New York, N. Y., a corporation of New York

Application June 15, 1939, Serial No. 85,500

Term of patent 7 years

To all whom it may concern:

Be it known that I, Agnes S. Selverstone, a citizen of the United States, residing at New York city, in the county of Kings and State of New York, have invented a new, original, and ornamental Design for a Textile Fabric or Similar Article, of which the following is a specification, reference being had to the accompanying drawing, forming part thereof.

The drawing shows a piece of fabric bearing my new design. The design is carried out in various colors or shades.

I claim:

The ornamental design for a textile fabric or similar article, as shown and described.

AGNES S. SELVERSTONE.
